UNITED STATES PATENT OFFICE.

FERGUSON S. HARDIN, OF LOS ANGELES, CALIFORNIA.

LEVER-LOCKING DEVICE.

968,659.

Specification of Letters Patent. Patented Aug. 30, 1910.

Application filed May 17, 1909. Serial No. 496,644.

To all whom it may concern:

Be it known that I, FERGUSON S. HARDIN, a citizen of the United States of America, residing at Los Angeles, in the county of 5 Los Angeles, State of California, have invented a certain new and useful Lever-Locking Device; and I do hereby declare the following to be a full, clear, and exact description of the invention, such as will enable 10 others skilled in the art to which it appertains to make and use the same.

This invention relates to a device for locking against movement a lever, such as the brake lever of a motor vehicle.

15 An object of the invention is to provide a portable device of the character mentioned that may be detachably applied to the lever rack bar of a motor vehicle without any alterations in existing parts thereof.

20 A further object is to provide a device which shall be equally applicable whether the lever is required to be moved to a forward position or moved rearwardly to apply the brake. A yet further object is to provide 25 a device that may be applied to motor vehicles having varying spaces between the lever rack bars.

Still further objects of the invention are to provide a device which shall be simple in 30 construction, cheap to manufacture, and easily applied in use.

Other objects and the advantages of the invention will be apparent, to those skilled in the art, from the following description of 35 forms of construction in which it may be embodied, taken in connection with the accompanying drawings, in which

Figure 1 is a perspective showing one form of the device in use; Fig. 2 is a perspective of the device; Fig. 3 is a perspective of a modified form of the device, and Fig. 4 is a longitudinal section of the modified form of the device.

40 Referring now to Figs. 1 and 2, the device preferably comprises a part 3 formed to fit the edge of the rack bar 4, and may be provided with side flanges 5 carrying the lugs 6 and 7, each of which has an opening 8 substantially in registry with the opening 45 in the other, and adapted to receive the link 12 of a padlock 13.

In the form of the device shown in Figs. 3 and 4, the part 14 is adapted to fit against the side and over the edge of the rack bar 4 50 and has lugs 15 and 16 which are preferably formed as shown in Fig. 3 and spaced from

the main body of part 14 to accommodate the rack bar 4 in the space thus provided.

The part 14 is provided with locking means which may comprise a cylindrical portion 18 revolubly mounted in said part 14 and held therein by an annular groove 19 into which the end of a screw 20, secured in part 14, enters. The outer end of portion 18 is provided with a head 21 of such proportions that in one position thereof it lies longitudinally of the main body of part 14, while in its transverse position relatively to the main body of part 14, it projects beyond the edge of the rack bar 4.

70 The cylindrical portion 18 has therein an opening for the insertion of a key 22, and also openings 23 in the cylindrical surface thereof, for the reception of one or more plungers 24 which are in registry with tumblers 25 in openings 26 in part 14. Openings 26 are closed by plugs 27 at their outer ends. Between plugs 27 and plungers 25 springs 28 are interposed.

75 As will be noted the parts 3 and 14 are made of such length that when the lever 10 is positioned to set the brake, they may extend between the lever and an abutment; which latter may be the piece 11 supporting the end of the rack bar.

80 In use the vehicle having been brought to a standstill and the lever moved to set the brake, the device may be applied to the rack bar between the brake lever 10 and the piece 11 supporting the end of the rack bar. The 85 device may then be locked in position. In the case of that form of the device shown in Figs. 1 and 2, the link 12 of the padlock 13 may be passed through the openings 8 and the padlock locked, or the device as shown in Figs. 3 and 4 may be locked in position by moving head 21 to occupy a position transversely of the main body of part 14.

90 As will be understood, by using the device in conjunction with the brake lever when it has been moved to set the brake, the vehicle on which it is applied cannot be moved by its engine or otherwise.

95 While one form of apparatus in which the invention may be embodied has been illustrated and described, it is obvious that various modifications and changes may be made, and the right is reserved to all such modifications and changes as do not depart from the spirit and scope of the invention.

100 What is claimed as new is:

1. In a device of the character described,

the combination of a lever, a rack bar arranged in coöperative relation to the lever, an abutment at one end of the rack bar, a locking member applied to one edge of the rack bar and interposed between the lever and the abutment to lock the lever against movement, the said locking member being bodily removable from the rack bar and being constructed so as to engage both sides of the rack bar, and means carried by the middle portion of the locking member for engaging the opposite edge of the rack bar to hold the said locking member in operative position upon the rack bar.

2. In a device of the character described, the combination of a lever, a rack bar arranged in coöperative relation to the lever, an abutment, a locking member fitting over one edge of the rack bar and interposed between the lever and the abutment to lock the lever against movement, a rotatable part carried by the locking member and adapted to engage the opposite edge of the rack bar to retain the locking member in position, and a key controlled plunger engaging the

rotatable part to hold the same in operative position.

3. In a device of the character described, the combination of a lever, a rack bar arranged in coöperative relation to the lever, a bodily removable locking member fitting over one edge of the rack bar and interposed between the lever and the abutment to lock the lever against movement, a rotatable part carried by the locking member and adapted to engage the opposite edge of the rack bar to retain the locking member in position, and key controlled means upon the locking member for retaining the rotatable part in operative position.

In testimony whereof, I have signed my name to this specification in the presence of two subscribing witnesses at Los Angeles, county of Los Angeles, State of California, this 7th day of May A. D. 1909.

FERGUSON-S. HARDIN.
